CLAIM

The ornamental design for a cable, as shown.

DESCRIPTION

FIG. 1 is a front perspective view of a cable showing my new design;

FIG. 2 is a top plan view thereof;

FIG. 3 is a bottom plan view thereof;

FIG. 4 is a right side view thereof;

FIG. 5 is a left side view thereof;

FIG. 6 is a front view thereof;

FIG. 7 is a rear view thereof;

FIG. 8 is an enlarged front perspective view thereof;

FIG. 9 is an enlarged top plan view thereof;

FIG. 10 is an enlarged bottom plan view thereof;

FIG. 11 is an enlarged right side view thereof;

FIG. 12 is an enlarged left side view thereof;

FIG. 13 is an enlarged front view thereof; and,

FIG. 14 is an enlarged rear view thereof.

The cable is shown with a symbolic break in its length in FIGS. 8-12 for ease of illustration. The appearance of the portions of the article between the break lines are shown in figs. 1-5, respectively.
